STANCHION

Stuart C. Lilly, London, Ohio

Application April 24, 1953, Serial No. 350,906

4 Claims. (Cl. 119—147)

1

My invention relates to a stanchion. It has to do, more particularly, with a stanchion which can be mounted in a barn door opening or similar opening or between two posts, inside or outside, for receiving and retaining the head of an animal.

My device is of a very simple and inexpensive structure. It is portable and can be carried by a veterinarian with his other equipment, in his car from farm to farm. To facilitate transportation from place to place it is so constructed that it can be disassembled or knocked-down readily without the use of tools. However, it can be reassembled and set-up easily also without the use of tools. It can be applied easily to a suitable opening and is adjustable to fit openings of various widths. It will automatically adjust itself to receive the head of the animal and when the head is inserted it can be actuated easily, from a remote location if desired, to prevent withdrawal of the animal's head from the stanchion.

The preferred embodiment of my invention is illustrated in the accompanying drawings wherein similar characters of reference designate corresponding parts and wherein:

Figure 1 is a face elevational view of a stanchion made according to my invention and set-up in a door opening.

Figure 2 is a horizontal sectional view taken on line 2—2 of Figure 1.

Figure 3 is an edge view of the stanchion.

Figure 4 is a top view of the stanchion.

Figure 5 is a diagrammatic view illustrating different adjustments of the animal-retaining slats.

Figure 6 is an enlarged detail of one of the spacer bolt units in my device.

Figure 7 is an enlarged detail showing the bayonet slot used in the lower end of each animal-retaining slat.

With reference to the drawings, I have illustrated my invention as comprising mainly an upper set of horizontal rails 10, a lower set of horizontal rails 11, and the associated vertical animal-retaining slats 12 and 13.

The lower set of rails 11 comprises the two rails 14 which are permanently joined together at their ends and are spaced from each other by the spacers 16 to provide the slot-receiving slot 17, and the cooperating clamping rail 15. The slot 17 receives the lower ends of the slats 12 and 13, the slat 12 being pivoted therein by the bolt 18 and the slat 13 being pivoted therein by the bolt 19, the two bolts 18 and 19 passing

through openings in the rails 14 and being permanently secured therein.

Associated with the bolt 18, as shown in Figure 6, is a spacer sleeve 18a. The bolt 19 is also provided with one of these spacers 19a. These spacers 18a and 19a (Figure 2) keep the two rails 14 properly spaced to provide the slot 11. The unit formed by the rails 14 (Figure 2) is adapted to be disposed at one side of the jambs J of the opening and the rail 15 is adapted to be disposed at the other side of the jambs. These members are connected in jamb-clamping relationship by the clamping bolt units 20. Each of these units comprises a bolt which passes through aligning longitudinal slots 21 in the rails 14 and a slot 22 in the rail 15. To adjust for different thicknesses of jambs the one end of the bolt is provided with a series of longitudinally spaced transverse bores 23 for receiving a locking pin 24, which will retain on the bolt a washer 25 adapted to engage the outer rail 14. The other end of the bolt, which is adjacent the rail 15, is provided with a wing nut 26 and an associated washer 27 which engages the rail 15. Obviously the bolt unit can be adjusted by resetting pin 24 for jambs of different thicknesses. Furthermore, it can be adjusted in slots 21 and 22 along the rails 14 and 15 in accordance with the width of the opening.

The upper set of rails 10 (Figure 4) is similar to the lower set 11, and includes the two joined rails 14a which are spaced by spacers 16a, the associated clamping rail 15a, and the adjustable clamping bolt units 20a with the wing nuts 26a and collars 27a. The upper ends of the slats 12 and 13 project upwardly through the slot 17a. The slat 12 is provided with an outwardly turned bayonet slot 18b at its lower end and the slat 13 is provided with an outwardly turned bayonet slot 19b at its lower end which engage with the sleeves 18a and 19a, respectively, of the bolts 18 and 19 in pivoting the slats to the lower rail unit 11.

To automatically swing the upper ends of the slats 12 and 13 outwardly, tension springs 28 and 29 (Figure 1) are anchored at their lower ends to the outer ends of the spaced rails 14 and at their upper ends to the outer edges of the respective slats 12 and 13, being anchored in channels 30 and 31 in the edges of the respective slats. The bolt units 20a serve as stops to limit outward swinging movement of the slats 12 and 13. Inward swinging movement of the slat 13 is limited by a transverse bolt 36 mounted in rails 14a but no means is provided for limiting in-

ward swinging movement of slat 12. Bolt 36 carries a spacer sleeve 36a (Figure 4) to maintain the spacing of rails 14a. If desired, for example when the stanchion is being used on small animals, a removable eye pin 35 may be inserted in transverse openings in rails 14a to hold the slat 13 vertical, engaging its outer edge to prevent outward swinging of this slat by the spring 29.

The slats 12 and 13 may be swung into co-operative relationship to retain the head of an animal by means of a rope 32 which is anchored to the upper end of the slat 13 and which slides through an opening in the upper end of the slat 12. Other ropes 33 and 34 may be anchored in openings 37 and 38 in the lower portions of the respective slats 12 and 13 for use in lifting the lower ends of the slats from the slot 17 of the lower rail unit 11 when desired.

With the stanchion mounted on the door opening as indicated, the upper ends of the two slats 12 and 13 will normally be spread apart by the action of the springs 28 and 29 or the spring 28 alone. Both slats will contact the bolts 20a or slat 12, as shown in Figure 1, will contact bolt 20a and slat 13 will contact pin 35. Obviously pin 35 will be removed if it is desired to spread the upper ends of slats 12 and 13 to maximum width. An animal can insert its head through the space between the slats 12 and 13 and then the slats can be pulled towards each other by means of the rope 32 to prevent withdrawal of the head. This rope may be sufficiently long so that the stanchion can be operated from a remote location. The rope 32 may be reversed. Anchoring cleats 40 are provided at each end of the rail unit 10 for anchoring the end of the rope to hold the slats together. As soon as the rope is released, the slats will automatically spread and permit withdrawal of the animal's head. As pointed out above, pin 35 may be removed to permit maximum spreading of slats 12 and 13. The spacing of the lower ends of the slats may be increased by lifting the bayonet slots 18b and 19b from the bolts 18 and 19 and permitting the springs 28 and 29 to pull their lower ends outwardly into contact with the bolt units 20, as shown by the dotted lines in Figure 5. This allows a spacing practically the full width of the door opening for large cattle to pass through. Springs 28 and 29 will hold the slats in fully opened position after the animal passes through. To narrow this spacing one or more of the slats may be positioned inside the bolts 18 and 19 as also shown in this figure by dotted lines. This is desirable for small animals.

The provision of the bayonet slots is important as it prevents the animal from raising the slats 12 and 13 out of the rail unit 11 since the outwardly directed ends 41 (Figure 7) of the slots will be in engagement with the spacer sleeves 18b and 19b. The spreading effect on the lower ends of the slats 12 and 13 by the animal will cause the engagement of ends 41 with the sleeves. When the animal is removed, the lower ends of the slats 12 and 13 may be pulled inwardly to position the vertical parts 42 of the bayonet slots in alignment with the spacer sleeves 18a and 19a. At this time, the slats 12 and 13 may be lifted from rail unit 11 by the ropes 33 and 34. Instead of ropes 33 and 34, the pin 35 may be used with openings 37 and 38 (Figure 5) to lift the slats 12 and 13 out of the slot 17.

The stanchion can be removed from the opening easily by removing the bolt units 20 and 20a. It can be knocked-down by lifting the slats 12 and 13 from the rail unit 11 and pulling them out of rail unit 10. It is merely necessary to remove wing nuts 26 and 26a and no tools will be required. My device can then be transported easily in knocked-down condition and obviously can be set-up readily in a different opening. The stanchion can be adjusted readily to fit openings of different widths and jambs of different thicknesses.

Various other advantages will be apparent.

Having thus described my invention, what I claim is:

1. A stanchion comprising upper and lower rail units including rails adapted to be clamped at opposite sides of vertical supports, connecting members in the form of clamping bolt units for holding said rails in clamping relationship, said lower rail unit including a pair of rails disposed at one side of the vertical supports and a single rail at the opposite side of the supports, relatively adjustable slats pivoted in a space between said pair of rails by means of bayonet slots in the slats and pins carried by said rails, said upper rail unit also including a pair of rails disposed at one side of the vertical supports and a single rail unit at the opposite side of the supports and being connected by bolt units, said slats extending upwardly between the pair of rails of the upper rail unit and being free to swing in the space provided therebetween, springs connected to the slats and anchored to the lower rail unit for normally swinging said slats apart, said bolt units of the upper rail unit serving to limit outward swinging movement of said slats, a rope anchored to the free end of one of said slats and slidably connected to the free end of the other to pull said slats towards each other, a stop pin carried by the upper rail unit for limiting inward swinging movement of one of said slats, and a removable pin carried by said upper rail for limiting outward swinging of said slat.

2. A stanchion according to claim 1 wherein each of the bolt units is adjustable as to length to clamp the rails to vertical supports of varying thicknesses.

3. A stanchion according to claim 2 wherein each of the bolt units passes through longitudinal slots in the rails of the rail units.

4. A stanchion according to claim 3 wherein said removable pin is spaced from said stop pin to limit outward swinging movement of the associated slat.
